Sidney K. Halpern, 74 Arleigh Road, Great Neck, N.Y.

Filed Mar. 16, 1964, Ser. No. 79,024

Term of patent 14 years

(Cl. D56—4)

FIG. 1 is a top perspective view of a radio, showing my new design;

FIG. 2 is a fragmentary perspective view of the center portion looking from the side opposite that seen in FIG. 1, and

FIG. 3 is a fragmentary bottom plan view thereof, the center piece which is broken away for convenience of illustration being the same in appearance as the portion shown.

The dominant features of my design reside in the portion shown in full lines.

I claim:

The ornamental design for a radio, substantially as shown and described.
